(57) **CLAIM**

The ornamental design for a toilet accessory caddy, as shown and described.

DESCRIPTION

FIG. 1 is a perspective view of a toilet accessory caddy showing our new design;

FIG. 2 is a left side view thereof, the opposite side being a mirror image of the side shown; and

FIG. 3 is a front elevational view thereof;

FIG. 4 is a rear view thereof;

FIG. 5 is a top plan view thereof; and,

FIG. 6 is a bottom plan view thereof.

The broken-line disclosure of a handle in the views is for illustrative purposes only and forms no part of the claimed design.
